Primary Examiner—Carol Rademaker*(74) Attorney, Agent, or Firm*—Lars S. Johnson; James D. Ryndak(57) **CLAIM**

The ornamental design for a bottle, as shown and described.

DESCRIPTION

FIG. 1 is a perspective view of a bottle showing the new design;

FIG. 2 is a front elevational view of the bottle depicted in FIG. 1, the opposite rear elevational view being identical, except for the unclaimed threads;

FIG. 3 is a right side elevational view, the left side elevational view being identical, except for the unclaimed threads;

FIG. 4 is a top view of the bottle depicted in FIG. 2; and, FIG. 5 is a bottom view of the bottle depicted in FIG. 2. The broken line environmental showing is for illustrative purposes only and does not form a part of the claimed design.
